UNITED STATES PATENT OFFICE.

SILAS E. BAILEY, OF ELMIRA HEIGHTS, NEW YORK, ASSIGNOR TO ELMIRA KNITTING MILLS, OF ELMIRA HEIGHTS, NEW YORK, A CORPORATION OF NEW YORK.

MACHINE FOR CUTTING AND FOLDING TAGS, LABELS, OR HANGERS.

Application filed August 16, 1927. Serial No. 213,397.

This invention relates to machines for cutting and folding tags, labels and hangers, and more particularly to the type which cuts these from tapes or ribbons which have 5 been previously made up, with the tags, labels or hangers, hereafter referred to as tags, in a continuous strip.

It is an object of the invention to provide a machine of this character for severing 10 the tags from the strip, tape or ribbon, hereafter referred to as tape, and folding and pressing the severed and unsevered ends or sides of the tags, all in one operation.

Another object of the invention is to make 15 a machine by which it is possible without change of adjustment to cut and fold tags of different widths and different lengths.

It is a further object of the invention to provide a machine of this character by means 20 of which tags of any desired dimension may be cut and folded.

It is a specific object of the invention to provide a machine of this character, all of 25 the parts of which are operated from a single shaft.

Another specific object of the invention is to provide a single cam device for operating all of the mechanism of the machine.

Still another detailed object of the invention is to provide a novel drive clutch for 30 the machine.

Other objects and features of novelty will be apparent from the accompanying drawings as the following description proceeds.

In the drawings:

Figure 1 is a plan view of my new machine;

Figure 2 is a side elevation thereof;

Figure 3 is a transverse vertical section 40 taken along the line 3-3 of Fig. 2;

Figure 4 is another vertical section taken along the line 4-4 of Fig. 1, and showing the driving clutch;

Figure 5 is a sectional view taken along 45 the line 5-5 of Fig. 4;

Figure 6 is a cross section through the head of the machine taken on the line 6-6 of Fig. 2;

Figure 7 is a section taken along the line 50 7-7 of Fig. 6;

Figure 8 is a detailed perspective view of the sliding member carrying the folding plates;

Figure 9 is a perspective view of the slid-

ing element carrying the knife for severing 55 the label;

Figure 10 is a perspective view of a tag in which the printing or design is lengthwise of the tape, after being cut and folded by my machine; and

60

Figure 11 is a similar view of a tag in which the printing or design is crosswise of the tape.

The machine in which my invention is embodied is designed for the cutting and folding of tags of all kinds, especially fabric. The stock from which the machine cuts the tags consists of either a plain tape, or one on which a lettering or design constituting the tag is printed or woven. In order to 70 apply the tags to manufactured articles, it is necessary to sever the tags one by one from the continuous tape and, also, to fold over the cut edges so that the tags can be sewed down at each fold, thereby leaving no 75 raw edge to be unsightly or unravel.

Heretofore, this process has been carried out by hand, or by faulty devices for performing certain of the steps. It is, therefore, the principal aim of my invention to 80 provide a machine which will perform this entire process in one operation. However, I find that many advantages accrue from a rearrangement of the steps, and hence the improvement of the process itself is another 85 aim of the invention.

Referring more particularly to the drawings for a detailed description of one embodiment of my invention, the machine as shown in Figs. 1, 2 and 3 comprises a fairly 90 heavy rectangular base 10, which may be cast or formed of sheet metal or other material as desired. Extending upwardly at substantially the center of the base 10 is a bent arm 11, which extends forward to the 95 front of the machine and terminates in an overhanging head 12, in which is mounted the mechanism for operating the moving knife 13 and the folding plates 14 and 15.

At the front of the machine, below the 100 head 12 is mounted a transverse guide member 16 on which the stationary knife 17 is fixed, and on which at either side thereof the presser blocks 18 and 19 are slidably mounted.

Upwardly extending lugs 22 and 23 are mounted on each side of the base at the rear of the machine, and are provided with

105

bearings 24 and 25 which journal the single drive shaft 26. A clutch indicated generally at 30 serves to transmit the power to the shaft from a free pulley 31, which is continuously rotated from some external source of power.

Referring more particularly to Figs. 2, 6 and 7, the construction of the knife blade and folding plate operating mechanism will first be described in detail. The transverse guide member 16, previously referred to, is secured to the base 10 by machine screws 34. A block 35 is adjustably secured in fixed position thereon by a set screw 36.

15 The head 12 is formed with a vertical rectangular slot in which the members carrying the knife blade 13 and the folding plates 14 and 15 are both slidably mounted. The slot is constructed in the head by forming a 20 rectangular recess in the terminal portion of the arm 11, and securing thereto a plate 38 as by means of screws 39 to form the rectangular slot 40.

Snugly fitted in the slot 40 is mounted a 25 sliding carriage 41. As shown in Fig. 8, this carriage is formed as a hollow rectangular box, open at the top and at one side. A portion of each side of the bottom 45 of the sliding member is cut away to receive 30 one of the folding plates 14 and 15 so that their outer edges will be flush with the outer surfaces of the carriage. These plates may be secured in position by screws 46, or any other securing means. The closed side 47 of 35 the carriage is provided with a threaded aperture 48 to receive a pin 49 to be later referred to.

Within the hollow sliding member, shown 40 in Fig. 8, is mounted a second sliding member indicated generally at 50, and shown in perspective in Fig. 9. A vertical groove 53 is cut in one rear corner of the block 50 to receive the spring 54 secured inside the sliding member as by means of a screw 55. 45 This arrangement holds the parts snugly in position and tends for a very smooth operation. The upper part of the member 50 is a solid rectangular block having a lower integral extension 57 which is shaped at its lower end to form or receive the reciprocating 50 knife 13. One face 58 of the block 50 is provided with a threaded aperture 59 to receive a pin 61 similar to the pin 49, and also to be later described in detail.

55 The parts shown in Figs. 8 and 9 are assembled in the head of the machine by first inserting the block 50 inside the carriage 41 with the spring 54 engaging the slot 53. The two elements are then inserted in the 60 rectangular slot 40, and the plate 38 is secured to the side of the head 12.

The presser blocks 18 and 19 are grooved to receive the guide member 16, and are slidably mounted thereon at either side of the stationary block 35 which carries the

fixed knife 17. Each of these blocks is recessed at its rear portion as at 65. As shown in Figs. 1 and 2, these recesses freely receive the ends of levers 66 and 67 respectively, which are pivotally connected to the 70 blocks by means of pins 68. These levers are fulcrumed intermediate their lengths upon screws 70, carried by bosses 71 formed on the machine base. The levers are thereby permitted to oscillate about their respective pivots in a horizontal plane. The rear ends of these levers are provided with rollers 72 and 73 respectively, forming followers for cams 105 and 106 to be later described.

As shown in Fig. 2, one side of the head 80 12 is slotted as at 75 to permit vertical movement of the pin 49. The pin 49 is threaded in the aperture 48 and extends outwardly of the sliding carriage 41, and through the slot 75, and engages the walls of the elongated 85 aperture 76 formed in the end of a lever 77, fulcrumed on a screw 78 secured to the side of the bearing arm 11. This arrangement permits the oscillation of the lever 77 about its pivot 78 in a vertical plane.

90 The plate 38 on the other side of the head is provided with a slot similar to the slot 75 through which the pin 61, which is threaded in the aperture 59, projects. This pin 61 extends outwardly to be received in an elongated slot formed in the end of a lever 80 similar to the slot 76. This lever is also fulcrumed on a screw such as 78, and permitted to oscillate in a vertical plane. Near their rear ends the levers 77 and 80 have laterally extending lugs 82 and 83 respectively, carrying rollers 84 and 85, constituting followers for the cams 86 and 87.

95 Intermediate the bearings 24 and 25, the shaft 26 has keyed thereto a cam device for 100 operating the mechanism of the machine. This cam has a peripheral track 86 which engages the roller 84, and another peripheral track 87 upon which the roller 85 rides. These tracks have substantially circular high 105 point dwell portions 89 and 90 respectively. The high point dwell of each peripheral cam is substantially ninety degrees, with a sudden drop as at 91 and 92 respectively, followed by a low point circular dwell portion 110 93 and 94, and a gradual lift 95 and 96 through the remaining ninety degrees to the high portion 89 and 90. The rollers 84 and 85 are yieldingly held against their respective cams by springs 100 and 101, which are secured to the ends of the respective levers and anchored to the base by pins 102.

115 Each side of the cam device is substantially flat, but provided with bumper cams 105 and 106 respectively. These bumper cams are adapted to engage the rollers 72 and 73 carried by the levers 66 and 67 respectively. A spring 107, connecting these levers, serves to normally hold the rollers in engagement with the faces of the cam. By this arrange- 120 125 130

ment, a low point dwell for a portion of each revolution is provided, with a sudden high point movement for about ten degrees, and correspondingly sudden return to the low point position.

With the movement imparted by the cam device just described, the lever 80 operates the reciprocating knife 13, the lever 77 operates the folding plates 14 and 15 and the levers 66 and 67 respectively, operate the presser blocks 18 and 19.

The clutch for operating the shaft from the free pulley 31 is shown in detail in Figs. 3, 4 and 5. A rectangular block 110 is keyed 15 to the shaft 26, and a yoke 111 is pivoted to each side of the rectangular block. Movement of the yoke in one direction is limited by a projection 112, and a leaf spring 113 normally urges it in the other direction. 20 The free pulley 31 is provided with laterally projecting spaced pins 114 with which the yoke 111 normally engages when urged outwardly by the spring 113.

The rear end of the machine base is provided with an upward extension 120, at the upper end of which is pivoted a curved lever 121 as by a bolt 122. Referring to Figs. 2 and 4, the lever 121 has the same curvature as the free pulley 31. As shown 25 in Fig. 1, the end of the lever is tapered as at 124, so that when the lever is in its lowered position the top of the yoke 111 will ride thereover and be moved back against the action of the spring 113. At about the 30 center of the curved portion is formed a slot 125 which will receive the top of the yoke and hold it in position free of the pins 114. The other arm 126 of the lever is provided 35 with a link 127 by means of which the lever 40 may be connected to an operating pedal (not shown).

In operation, when the pulley 31 is driven from an external source of power, the clutch lever 121 is normally in the position shown 45 in full line in Fig. 4. When the operating pedal is depressed, the lever is raised permitting the spring 113 to urge the top of the yoke 111 into contact with the pins 114 on the driven pulley 31. Power will thereby 50 be applied to drive the shaft 26.

As the shaft revolves, the raised incline 96 of the cam surface 89 will elevate the roller 85 and cause the front end of the lever 80 to be depressed. The pin 61 carried by the 55 lever 80 will drive the block 50 downward and cause the blade 13 carried thereby to contact with the fixed knife blade 17 and sever the tag. Then the high part 89 of the cam 86 will raise the roller 84 which will cause 60 the front end of the lever 77 to lower the pin 49 carried thereby, and will drive the sliding carriage 41 downward, so that the folding plates 14 and 15 will be operated.

It will be evident from Fig. 1 that the 65 bumper cams 105 and 106 engaging the roll-

ers 72 and 73 will cause the presser blocks 18 and 19 to move toward each other. The cam device is so timed that the roller 84 rides off the high part 89 of the cam 86 just as the side bumper lugs 105 and 106 70 come into contact with the rollers 73 and 74, which operate the presser blocks.

A reference to Figure 6, which shows the presser blocks 18 and 19 extended to their maximum, will indicate when a tag is cut 75 by the action of the stationary and movable knives that the severed portions of the tape will rest on the block 35 which carries the stationary knife while the main portions of the tape and the severed tag will rest on 80 the presser blocks. Immediately after the cutting the folder plates 14, 15 move downwardly. They cooperate with the edges of the presser blocks to fold the severed ends 85 of the tag and tape into the slots between the presser blocks and the knife-holding block 35. These ends are of such length that they will, by the resilience of the material, press inwardly against the sides of the block 35 and thus be held in the slot even 90 after the withdrawal of the folder plates. Immediately upon the withdrawal of the folder plates the presser blocks move inwardly carrying with them the severed ends 95 of the tape and tag so that the turned down ends thereof are pressed between the vertical faces of the presser blocks and the vertical sides of the knife-carrying block 35. The top surface of this knife-carrying block is higher than the top surfaces of the presser 100 blocks and there are wings arranged laterally thereon, under which the top surfaces of the presser blocks can just pass. When the pressing operation takes place the material of the tag and tape is pressed between 105 the under surface of a wing and the upper surface of a presser block as well as between the vertical faces of the presser block and knife block. This insures the folding of a sharp crease in the fabric as a result of placing both sides of the crease against right angled faces of the presser block. The action 110 of the upper face of the presser block and the under face of the wing is almost a shearing one to insure an extremely sharp 115 crease.

With the cam device so timed, it will be apparent with reference to Fig. 6, that by the operation just described the folding plates 14 and 15 will be in the lowered position. Just as these are raised, the presser blocks 18 and 19 move against the block 35, and press the crease which has been partly formed by the folding plates. As soon 120 as the bumper cams 105 and 106 ride clear of the presser block rollers 72 and 73, the blocks 18 and 19 are immediately separated. The tip of the yoke 111 will then engage 125 the point 124 of the curved lever, and will ride along the tapered surface thereof until 130

it is free of the pins 114 and will lodge in the slot 125, which will prevent further operation until the clutch lever is again tripped.

To use the machine, the operator will therefore locate the end of the continuous tape so that the knife blade is positioned between two adjacent designs, or at such point as it is desired to cut the tape. He will then depress the operating pedal and the machine will sever the tape, and fold over the severed, as well as the unsevered ends of the tape in one operation. Then he will move the tape on to either the division line between the unfinished tag and the next, or to such place as he desires to cut, if a plain tag, and again depress the pedal. The machine will then complete the unfinished tag and start the manufacture of the next succeeding tag. The operation of the machine, therefore, is independent of the dimension of the tag, hence by this machine and process, tags of any desired dimension may be cut and folded.

While one embodiment of the invention has been described in such detail that anyone skilled in the art may readily construct the same, the specific details given are intended in a descriptive, and not in a limiting sense. The invention, therefore, is not limited to the embodiment shown but includes such modifications as come within the scope of the subjoined claims.

Having thus described the invention what is claimed as new and desired to be secured by Letters Patent is:

1. A machine for cutting and forming tags from a tape, comprising in combination, a base, an arm thereon having a head, a reciprocating knife mounted in said head, a stationary knife mounted on said base to cooperate therewith, blocks on each side of said stationary knife, folding plates in said head cooperating with said blocks, a shaft journaled on said base, and means thereon for operating said reciprocating knife and folding plates.

2. A machine for cutting and forming tags from a tape, comprising in combination, a base, an arm thereon having a head, a reciprocating knife mounted in said head, a stationary knife mounted on said base to cooperate therewith, shoulders on each side of said stationary knife, folding plates on said head adapted to pass beside said shoulders, presser blocks slidably mounted on said base for movement to and from said shoulders, and means for operating said reciprocating knife, folding plates, and presser blocks.

3. A machine for cutting and forming tags from a tape, comprising in combination, 60 a frame, a head mounted thereon, a reciprocating knife mounted in said head, folding plates mounted on each side of said knife, a base, a stationary knife mounted thereon to cooperate with said reciprocating knife, shoulders on each side of said stationary knife, and a pressing block movably mounted at each side of the stationary knife for cooperation with the shoulders.

4. A machine for forming tags from a 70 tape, comprising in combination, a base, a stationary knife, a shoulder on one side thereof, a reciprocating knife mounted to cooperate with said stationary knife, a folding plate adapted to pass by said shoulder, 75 and a presser block mounted on said base to slide to and from said shoulder, and means operated in timed relation to said knife for moving said folding plate between said shoulder and block, and withdrawing 80 it as the block moves toward said shoulder.

5. A machine for cutting and folding tags from a tape including in combination, a base, a head supported above said base, a reciprocating knife in said head adapted to cooperate therewith, a presser block on each side of said stationary knife, a folding plate movable in said head to cooperate with each block, an abutment on each side of said stationary knife and means to move said blocks 90 into cooperation with said abutments.

6. A machine for cutting and folding tags from a tape including in combination, a base, a stationary knife thereon, a carrier for said knife having laterally overhanging wings, a head, a movable knife carried by said head, a presser block on each side of said carrier and each movable beneath one of said wings, a pair of folding plates supported in said head for movement to cooperate with said blocks when separated from said wings and means to first move said knife, then said folding plates and then said presser blocks for the purpose described.

7. A tag folding mechanism comprising an abutment having an overhanging wing, a presser block normally spaced therefrom, a folding blade adapted to fold a tape over the edge of said block and means to move said block and tape against said abutment and in cooperative relation to said wing to crease the tape.

In testimony whereof I hereunto affix my signature.

SILAS E. BAILEY.
